APPARATUS WITH MOVABLY MOUNTED SPOON MAGAZINE FOR INSERTING SPOONS IN CARTONS

Leo Kulpinski, Wausau, Wis., assignor to Marathon Corporation, Rothschild, Wis., a corporation of Wisconsin

Application January 17, 1949, Serial No. 71,341

4 Claims.

(Cl. 226—2)

1 This invention relates to a machine for automatically inserting flat wooden spoons in a pocket portion provided in cartons.

The apparatus comprises means for conveying a series of flat collapsed cartons provided with a pocket portion to a spoon inserting station where means are provided for feeding one spoon at a time from a magazine and for inserting the spoon in the pocket portion of the carton.

Large quantities of single slices or helpings of ice cream, sherbet, frozen ices and desserts and the like are sold in paper cartons or packages which may be provided with a hinged cover adapted to be opened so that the consumer may eat the food directly from the container by means of a wooden spoon or other implement that may be provided. Such packages are sold on trains, amusement places, parks, refreshment places and in outdoor stands. It has been customary to give the consumer a spoon with each purchase or to place a spoon loosely inside the package which the consumer can use for eating the food products. When spoons are inserted within the package they are often lost or misplaced.

In order to overcome this difficulty, cartons have been designed which are provided with a pocket portion for receiving a spoon. One such carton construction is disclosed in copending application Serial No. 786,029 filed November 14, 1947, and now issued as U. S. Patent 2,509,616. The pocket portion is formed by folding over one of the flaps of the carton and gluing its margins to the body of the carton so as to form a pocket portion within which a wooden spoon or other implement may be inserted and in which it will be securely retained while being shipped or stored until it is used by the consumer. The pocket portion occupies relatively little space and is constructed in such manner that it is a functional part of the package and does not unduly bulk or bulge the package or deform it in any way. Before or after opening the cover of the carton or container it is possible to readily remove the spoon or other implement by merely slipping it out of the pocket portion for convenient use.

It has been found very laborious and inconvenient to insert spoons in such pocket portions by hand. Furthermore, it is undesirable from the viewpoint of cleanliness and sanitation to handle such spoons. The present invention provides means for overcoming this problem by providing automatic means for inserting spoons in the pocket portions of the type of cartons previously referred to.

2 Details and advantages of the inventions will be apparent from the following specification and drawings, wherein

Figure 1 is a perspective view of the spoon inserting apparatus,

Figure 2 is a side elevational view of the apparatus shown in Figure 1, partly in section, and

Figure 3 is an enlarged plan view partly broken and in section taken along lines 3—3 of Figure 2.

Referring to the drawings, the flat collapsed carton, indicated by numeral 10, is provided with a pocket portion 13 for receiving a flat wooden spoon 12. The upper part of pocket portion 13 is cut away at 11 to provide a gripping area for spoons carried in the pocket. A stack of aligned spoons 12 is retained in a magazine 65. The individual spoons are fed one at a time from the bottom of the magazine by means of an automatically operated slide 20 which is reciprocated by means to be described later.

The cartons 10 are conveyed on a pair of spaced chain conveyors 14 which are provided with suitably spaced lugs 15 for holding the cartons in properly spaced relation and to move them toward the spoon inserting station.

The spoon inserting unit comprises a reciprocating slide 20 which is carried by a head 21 reciprocating on a rocking arm 60. The rocking arm 60 is pivoted on shaft 52 so as to rock thereon. A coiled compression spring 61 is provided beneath the rear end of arm 60 against which the arm is yieldingly rocked. The spring tends to normally rock the forward end of arm 60 downwardly toward the frame member 5. The opposite end of the rocking arm 60 carries a magazine 65 for holding a stack of aligned spoons 12. The magazine is also provided with guy rods 66 attached to arm 60 to fixedly secure the magazine to the arm 60. A weight 67 rests on top of the stack of spoons so as to feed the spoons toward the bottom opening of the magazine.

Reciprocating slide 20 is actuated by link 23 which is pivoted eccentrically on a rotating disc 25 mounted on shaft 27. Shaft 27 is rotated by bevel gear 28 which in turn is driven by bevelled gear 29 on shaft 30. Shaft 30 is driven by a sprocket 31 and chain 32 connected to and driven by a motor, not shown.

Shaft 27 also carries a cam 40 having a cam track 41 which engages with a follower roll 42 carried on a bracket 44 integral with rocking arm 60 as shown in Figure 2. The magazine 65 is provided with a bracket 75 which carries a rod 68 having a tamping element 69 at the lower

end thereof for contacting the cartons as the rocking arm tilts downwardly toward the frame member so as to contact the carton 10 positioned therebeneath.

In operation, the cartons 10 are conveyed on the spaced chain conveyer 14 intermittently so as to bring an individual carton to rest at the spoon inserting station. Shaft 27 is rotated in fixed relation with the travel of chains 14 so as to rock arm 60 to the position shown in Figures 1 and 2. At the same time crank arm 23 reciprocates the slide 20 beneath the open end of the magazine 65 so as to eject a single spoon 12 into the pocket portion 13 of the carton. The forward bottom edge of the magazine 65 is provided with protuberance 70 which engages the body of the carton and slightly depresses it adjacent and forwardly of the opening of the pocket portion as shown in Figure 2. At the same time the tamping element 69 engages the body of the carton so as to retain it in place while the spoon is being inserted into the pocket portion 13. Further rotation of the shaft 27 depresses the rear end of the rock arm 60 so as to cause the forward end to tilt upwardly carrying with it the magazine, reciprocating slide and tamper. The carton is then conveyed past the spoon inserting station and another carton is positioned in place for receiving a spoon. This operation is repeated continuously.

Other variations and modifications in the above described embodiments will be apparent to those skilled in the art and no limitations are intended thereby except such as are contained in the following claims.

I claim:

1. An apparatus comprising a conveyor, means on said conveyor for positioning a carton blank relative thereto, said carton blank having a pocket therein, means for intermittently moving said conveyor whereby cartons thereon are carried to an inserting station, a support mounted for arcuate movement in a vertical plane, means for moving said support in such plane from an upper to a lowermost position, a magazine carried by said support for articles to be inserted into the pocket of said carton blanks, a reciprocating slide movable in a plane parallel to and closely adjacent said magazine support adapted to engage and eject an article from said magazine when said magazine is moved to its lowermost

position, and means whereby said reciprocating slide moves said article into said pocket when said magazine is in its lowermost position adjacent the open end of said pocket.

2. The apparatus of claim 1 including means on said magazine adapted to open the pocket in said carton when said magazine is positioned adjacent the open end of said pocket.

3. An apparatus comprising a conveyor, means on said conveyor for positioning a carton blank relative thereto, said carton blank having a pocket therein, means for intermittently moving said conveyor whereby cartons thereon are carried to an inserting station, a support mounted for arcuate movement in a vertical plane including a rocking arm, a cam for moving said support in such plane from an upper to a lowermost position, a magazine carried by said support for articles to be inserted into the pocket of said carton blanks, a reciprocating slide mounted on said arm and movable in a plane parallel to and closely adjacent said magazine support adapted to engage and eject an article from said magazine, a crank associated with said cam for reciprocating said slide, said cam and said slide being designed and arranged whereby said reciprocating slide moves said article into said pocket when said magazine is in its lowermost position adjacent the open end of said pocket and whereby said magazine moves away from said carton blank after insertion of said article to permit said carton blank to be moved by said conveyor away from said inserting station.

4. The apparatus of claim 3 including a tamper and a protuberance secured to said magazine and positioned to hold cartons in position at said inserting station and to depress a portion of the carton immediately adjacent the open end of the pocket whereby said pocket is opened to receive said articles.

LEO KULPINSKI.
